UNITED STATES PATENT OFFICE.

JOHN M. PULEY, OF CLEVELAND, OHIO.

FOLDING BOX.

953,761.

Specification of Letters Patent.

Patented Apr. 5, 1910.

Application filed April 7, 1909. Serial No. 488,398.

To all whom it may concern:

Be it known that I, JOHN M. PULEY, a citizen of the United States, and resident of Cleveland, in the county of Cuyahoga and State of Ohio, have invented certain new and useful Improvements in Folding Boxes, of which I hereby declare the following to be a full, clear, and exact description, such as will enable others skilled in the art to 10 which it appertains to make and use the same.

The objects of the invention are to provide a collapsible box suitable for use by tailors, department stores, laundymen, and others who require the use of a large number of light and serviceable boxes, and who therefore prefer to use a form of collapsible box which can be stored in flat sheets until needed when they can quickly be put into 20 shape.

The box is also arranged to be self securing and when folded upon predetermined lines forms an integral box and cover, with interlocking parts, and hence seldom requires 25 the use of a string to secure the cover in place.

The invention has reference also to a holding device whereby the box can be easily carried in one hand, and the engaging parts 30 be in no danger of separating.

To accomplish these objects the box is cut from one integral sheet, in which the lines for folding are marked or deeply scored so that any one can make up the boxes, as they 35 are required.

The invention consists in the combination and arrangement of the various parts, as hereinafter described, shown in the accompanying drawings and specifically pointed 40 out in the claims.

In the accompanying drawings, Figure 1 is a perspective view of the box, in a partially open position, showing the manner of combining the interlocking parts; Fig. 2 is 45 a plan view of the extended sheet from which the box is to be formed, showing the lines upon which the folds are made.

In these views 1 is the bottom portion, and 2 is the cover, 3 is the rear side portion 50 which connects the bottom and cover, 4 is the front side or flap of the bottom portion and 5 is the front side of the cover, 6, 6 are the end portions of the bottom and 7, 7 are the end portions of the cover.

55 The front side ends of the bottom portion are separated from each other and from the

rear side, and preferably have rounded corners, 8, 8 to make their insertion in the folds of the locking portions easier.

The flat sheet, shown in Fig. 2 is scored 60 on lines 9, 9, parallel to its edges, for ready folding to form the end and side walls.

The corners 10, 10 and 10' or rectangular spaces formed between the intersecting lines 9, 9, in the cover portion are not wholly cut 65 away but are left intact at 10, 10 at the front side of the cover, and only partially cut away at 10', 10' at the rear side, if desired.

Each corner is diagonally and substantially centrally scored at 12, on the outer side of the sheet to permit of binding the corner inwardly to form a reentering fold, as 13, 13 shown in Fig. 1.

This construction permits of closing the 75 box in the manner shown in Fig. 1 so that the sides of the bottom will be inserted between the outside faces of the reentering folds, and the side walls of the cover as shown at 14, 14. As the cover shuts down 80 still farther the front side 4 of the bottom enters between the front edge of the folds 13, 13 at 15 15 and the front wall 5 and the pressure of the folds against the sides, is sufficient in heavy material to form a secure lock, which will not readily come apart.

In Fig. 1 is shown a band or tape T which is looped at its ends at t, t, and passed around the box through openings 90 R, R. This tape is used to hold the box when carrying it.

Having described the invention what I claim as new and desire to secure by Letters Patent is:

1. In a collapsible box, in combination integral bottom, top, side and end portions respectively, the lines for bending the same scored thereon parallel to the edges thereof, the front, side and ends of the bottom portion being free at their adjacent edges, integral corner pieces connecting the sides and ends of the cover portion, said corner pieces being centrally and diagonally scored to form reentrant folds between which and 105 the adjacent side walls the sides and ends of the bottom portion are adapted to be inserted, all parts automatically locking together when the box is closed.

2. In a collapsible box, an integral sheet 110 forming bottom, cover, and front and rear and end portions respectively, the front and

end portions of the bottom being detached from each other and from the rear side thereof, and integral corner portions included between the end and side portions of the cover, said corner portions diagonally scored and adapted to be folded in the score lines to form reentrant angles, all said end and side portions adapted to be bent upon score lines, said score lines running parallel to the edges of said sheet, the ends of said bottom portion being adapted to be inserted between said reentrant angular folds in front and rear and the end por-

tions of the cover, and said front of said bottom portion adapted to be inserted between the reentrant angular folds in the front of the box, and the front of the cover, and adapted to lock the box portions together. 15

In testimony whereof, I hereunto set my hand this 2nd day of April 1909.

JOHN M. PULEY.

In presence of—
GEO. S. COLE,
Wm. M. MONROE.
